UNITED STATES PATENT OFFICE.

WILLIAM E. WINE, OF TOLEDO, OHIO.

DOOR MECHANISM FOR RAILWAY CARS.

Application filed April 16, 1923. Serial No. 632,414.

My invention relates to door mechanism for railway cars of the drop bottom or hopper type, and is particularly directed to the provision of strong, simple, reliable and efficient means for maintaining the swinging doors of the car in closed position.

A primary feature of the invention consists in constructing the hinged door with an outstanding marginal flange along an edge thereof, and in securing a channel member to the under side of said door in inverted U position, a flanged member, having a downwardly offset portion passing beneath said marginal flange and projecting beyond the adjacent edge of the door, being secured to said channel member within the channel thereof, and means mounted upon a stationary part of the car body being provided for cooperating with said flanged member to support the door in closed position.

Still another feature of the invention consists in supporting the hinged door of a car in closed position by means involving an arm mounted upon the door and projecting beyond an edge thereof, a hook or latch adapted to releasably engage said arm, and means for pivotally mounting said latch upon a stationary part of the car, the means by which the latch is mounted upon the car comprising a plurality of pivot brackets between which a portion of the latch extends, the innermost of said brackets having a plurality of inwardly projecting bosses of unequal length the longer of which is adapted to engage a side sheet of the car and the shorter of which is adapted to engage a reinforcing member secured to the outer face of said sheet.

In the drawings illustrating the preferred embodiment of the invention, the scope whereof is pointed out in the claims,—

Figure 1 is a view, partly in side elevation and partly in vertical section, showing a portion of the car equipped with devices embodying the invention.

Figure 2 is a detail sectional view on the line 2—2 Fig. 1, looking in the direction of the arrows, the hinged door being in closed position and the door supporting latch or hook being locked against accidental release.

Figure 3 is a detail plan view of a portion of the hinged door, illustrating the relation of the door supporting arms thereto.

Figure 4 is a detail view, partly in elevation and partly in section, showing the relation of the supporting arms to the door.

Figure 5 is a detail view showing a modified form of door supporting hook or latch and its relation to the cooperating door supporting arm.

Figure 6 is a view corresponding to Fig. 5 but illustrating another modified form of door supporting hook.

The car shown in the drawings for the purpose of illustrating the invention is of a well known type having one or more pairs of doors 1 which are hinged to the car body 2 by means of suitable hinges 3. When in locked position these doors close the discharge opening of the hopper of the car, the said hopper in the form of car illustrated being constructed with hopper slope sheets 4 and side sheets 5. The doors 1 are preferably inclined so that they slope downwardly from their hinged edges toward the center of the hopper discharge opening, which not only increases the carrying capacity of the car but also renders the door supporting mechanism more accessible and at the same time facilitates the closing of the doors by avoiding the necessity of lifting them to the horizontal position. The lower end of the side sheet 5 bordering the hopper discharge opening of the car is preferably sloped or inclined to correspond to the slope of the doors when in their closed positions; and the said sheet is preferably reinforced at said discharge opening by a bar or plate 6 riveted to the outer face of said sheet and conforming to the slopes of the bottom edge thereof.

Each of the doors 1, which may advantageously be formed with marginal stiffening flanges 7, is reinforced adjacent its edge remote from its hinges by means of a flanged member 8 of channel cross section securely riveted to the under side of the door and preferably arranged in inverted U position. The flanged member 8 may advantageously extend substantially the full width of the door.

Rigidly secured to the opposite ends of the flanged reinforcing member 8 within the channel thereof are door supporting arms 9 which project beyond the correspondingly adjacent ends of said flanged member and extend beyond the respectively adjacent edges of the door 1. The door supporting arms 9, which constitute brackets for cooperating with latch mechanism carried by a stationary part of the car preferably are formed as flanged members of angle iron cross section, thus enabling rolled commercial angle irons to be used for this purpose, although the

members 9 may be formed as castings if desired. Each of the flanged supporting arms 9 is offset downwardly at its outer end as indicated at 10 so as to pass beneath the adjacent marginal flange 7 of the door; and the depending leg of each door supporting arm may be provided with an aperture 11 for receiving a removable lever or prying bar that may be employed in forcing the doors to closed position. The procumbent leg 12 of the angle iron bracket 9 affords a seat adapted to be releasably engaged by a movable hook or latch which serves to prevent the door from executing an opening movement. It will be perceived that the elements of the door locking mechanism which are carried by the door are so formed and arranged that they are compactly disposed, easily applied, simple and strong in construction and efficiently reinforce the door.

The means for cooperating with the respective supporting arms 9 to sustain the doors against opening movements preferably involve a plurality of latches or hooks 13 which are pivotally mounted upon a stationary part of the car, as for example, by means of the respective rivets 14. Each hook 13 is formed with a shoulder or ledge 15 adapted to extend under and engage the adjacent flange 12 of the supporting arm 9 carried by the door with which it is associated. The hook may also advantageously be provided with an auxiliary or secondary ledge 16 which, as shown in Fig. 1, is also adapted to cooperate with the upper leg or ledge 12 of the adjacent supporting arm, means thus being provided for supporting the door in a partially closed position. It is desirable to provide the hooks 13 with auxiliary ledges 16 because, as is well known, the swinging doors of hopper cars may very readily be raised until they nearly assume closed position, but by reason of warping of the doors considerable force is usually required to bring them to fully closed position. By providing the hooks with the auxiliary ledges 16 the doors may conveniently be brought to a partially closed position and then may be forced to final closed position by the use of a removable lever or prying bar inserted through the aperture 11 of the appropriate door supporting arm 9.

The upper portions of the hooks 13 extend between bracket members 17 and 18, respectively, which are rigidly riveted to the car. The lower portion of the innermost bracket 18 overlaps the bar or plate 6 reinforcing the lower edge of the side sheet 5 at the hopper discharge opening, and the said bracket is provided upon its inner side with a plurality of inwardly extending bosses 19 and 20, respectively. The upper bosses 19 are of sufficient length to extend over the reinforcing bar 6 and engage the sheet 5 of the car, while the shorter bosses 20 engage the outer face

of said bar. The several bosses are perforated to receive rivets by which the brackets are secured in place. The inner bracket member 18 which serves as a filler for spacing the hooks outwardly from the reinforcing plate 70 6 is, as shown, preferably made of greater height at its center than towards its ends, thus enabling it to function efficiently as a beam for distributing the load from the door hooks to the reinforcing plate and the hopper sheet. Pivotally mounted between the brackets 17 and 18 and operatively associated with the respective hooks 13 are locking cams 21 which when the hooks 13 support the door in closed position, may be rotated so as to stand behind the hooks and prevent their accidental release.

The door supporting hooks illustrated in Figs. 5 and 6 are unprovided with auxiliary ledges. In the construction shown in Fig. 5 the hook 22 is provided below its shoulder or locking ledge 23 with a shoulder 24 which, when the door is in closed position, is spaced from the depending leg of the door supporting arm 9 a distance sufficient to permit introduction of a bar so as to enable the hook to be readily released from supporting engagement with the said arm.

The hook 25 illustrated in Fig. 6 likewise is provided with a shoulder 26 for cooperating with the door supporting arm 9 to retain the door in closed position. In this form of hook, whose lower end 27 is curved so that the door arm 9 may readily slide along it in the operation of closing the door, an outstanding lug or shoulder 28 is provided to form a seat enabling a bar to be used for releasing the hook from the door supporting arm, as heretofore described.

I claim:—

1. In a car door mechanism, the combination with a hinged door having an outstanding marginal flange, of a channel member secured to the under side thereof in inverted U position with the legs of the channel substantially normal to the door, an angle iron secured to said channel member within the channel thereof, said angle iron being bent intermediate its ends, one end thereof projecting beyond the adjacent edge of the door, the procumbent leg of the projecting portion of said angle iron being in a plane substantially parallel to the plane of the door, and means mounted upon a stationary part of the car and operating in a plane normal to said procumbent leg for engaging the latter to support said door in closed position.

2. In car door mechanism, the combination with a hinged door, of means for supporting said door in closed position, said means involving an arm mounted upon said door and projecting beyond an edge thereof, a hook adapted to engage said arm, and means for pivotally mounting said hook upon a stationary part of the car, said last named means

involving a plurality of pivot brackets between which a portion of said hook extends the inner of said brackets being provided with a plurality of inwardly extending bosses of unequal length, the longer being adapted to engage a side sheet of the car and the shorter being adapted to engage a reinforcing bar secured to the outer face of said sheet.

3. In car door mechanism, the combination with the side sheet of a car hopper, said sheet having a downwardly and inwardly inclined portion, and a vertically extending portion below the latter, of a plurality of hinged doors for closing the discharged opening of said hopper, said doors extending outwardly beyond said vertical portion of the hopper side sheet, a plurality of hooks pivotally mounted upon the car body, means mounted on said doors adapted to be engaged by said hooks to support said doors in closed position, a reinforcing member secured to the outer face of said hopper side sheet, a member interposed between said reinforcing member and said hooks for spacing the latter from said reinforcing member, said member having inwardly extending bosses engageable with the side sheet and reinforcing member and means extending over said hooks and rigidly connected to said spacing and reinforcing members.

4. In a car door mechanism, the combination with the side sheet of a car hopper having a vertically extending lower portion, of a plurality of doors for closing the discharge opening of said hopper, said doors when closed being in inclined planes and each having an edge extending outwardly beyond said vertically disposed portion of the hopper side sheet, a reinforcing member secured to the outer face of said side sheet adjacent the lower edge of the latter, a plurality of pivotally mounted hooks, means mounted on said doors adapted to be engaged by said hooks to support said doors in closed position, a filler member interposed between said reinforcing member and said hooks, said filler member being provided with a plate portion having bosses projecting inwardly therefrom for spacing the hooks from the side sheet and means extending through said hooks and

filler member for forming pivots for said hooks.

5. A railway car having a hopper provided with means reinforcing the discharge opening thereof, a door for closing said opening, means for supporting the door in closed position involving a member fixed to the door and a hook member pivoted to the car body, and a filler casting interposed between the reinforcing means and hook, said casting having a plate-like portion and a plurality of bosses extending inwardly therefrom toward the hopper for spacing the hook outwardly of the latter, said bosses being arranged for engagement with the reinforcing means and the hopper sheet and being so proportioned that the plate portion of the casting will be disclosed in a plane substantially parallel to the plane of operation of the pivoted hook.

6. A railway car having a lading discharge opening, a door for closing said opening movable to open position under the influence of gravity, a fixed member carried by the door, and a movable member pivoted to the car body having a ledge engageable with the fixed member for supporting the door in closed position, said movable member being provided below the ledge with a portion for accommodating a removable lever adapted to pry the latter to door releasing position, the said portion being fashioned so that the lever may be free to move downwardly when the door gravitates to open position.

7. A railway car having a lading discharge opening, a door for closing said opening movable to open position under the influence of gravity, a fixed member carried by the door, and a movable member pivoted to the car body having a ledge and an approach plane leading thereto, said ledge being engageable with the fixed member for supporting the door in closed position, the said approach plane having a recess for receiving a removable lever adapted to pry the hook to door releasing position, the recess being so formed that the lever may be free to move downwardly when the door gravitates to open position.

In testimony whereof I affix my signature.

WILLIAM E. WINE.
